UNITED STATES PATENT OFFICE.

BENJAMIN E. BATES, OF CHICAGO, ILLINOIS, ASSIGNOR TO WILSON-WESTERN SPORT-
ING GOODS COMPANY, OF CHICAGO, ILLINOIS, A CORPORATION OF DELAWARE.

HELMET OR HEADGUARD.

Application filed October 15, 1926. Serial No. 141,843.

The invention relates to helmets or head guards for use by athletes and others, and is particularly useful in protecting the heads of football players from the blows and impacts of opponents. It is also useful in adding to the comfort of the player.

One of the principal objects of the invention is to provide an inner crown member in the head guard which is arched to fit the player's head, and which has tabs at the front, rear and sides of the player's head, and which is adjustably and removably secured in the head guard.

It is one of the objects of the invention to provide an inner crown protector which may readily be arranged to fit heads of various sizes and shapes, and which may be raised or lowered within the upper portion or chamber of the head guard so that the greatest comfort may be secured for the player when wearing the head guard.

A further object of the invention is to provide an inner crown member which serves as an auxiliary protection to the interior cushion of the head guard, which is relatively soft and resilient, and which is secured to the outer protective shell of the head guard.

An additional object of the invention is to supply an inner crown member which fits snugly against the head of the player, but which is very light in weight, and which, being a substantial distance from the main body of the head guard, which is relatively stiff and heavy, provides a large air cushion between the auxiliary inner crown member and the main crown of the head guard. This large air cushion lying between the inner crown member and the main crown is thoroughly ventilated with apertures to the exterior atmosphere, and a constant circulation of fresh air is provided and furnished to the head of the wearer of the head guard. By means of the invention the player has the feeling of the light weight head covering, the ventilated air cushion above, and knows that above that he has the main cushion of the helmet and the outer protective covering or shell. With this sense of comfort, due to the light weight auxiliary inner crown member, the cool air cushion and the outer protective shell, the player can play a good game with a feeling of safety and protection.

It is another object of the invention to

provide the inner auxiliary crown member in a separate piece of material, which, with its securing cords or laces, may be adjustably secured in any helmet or head guard not theretofore provided with such an auxiliary crown member. By inserting apertures into the helmet or head guard not theretofore provided with the auxiliary crown member, such a member may be readily and adjustably fitted and secured in the helmet or head guard.

One of the great objections to employing soft cushioning material in a football helmet is that the cushion becomes hard and matted because of the excessive amount of perspiration from the player's head. The helmet also becomes somewhat unsightly and unclean. The auxiliary inner crown member reduces this to a considerable extent, and in the event that the auxiliary crown member becomes unsightly or objectionable for any reason, it may be replaced by a new, clean member.

The auxiliary crown member may be made of any suitable material, such as canvas, rubberized fabric, or the like. It will be obvious that the auxiliary inner crown member may, in itself, be supplied with ventilating openings.

It is also obvious that the inner auxiliary crown piece may be of various sizes or shapes, and may have any desired number of tabs by which it may be adjustably and removably connected, at different points or places in the outer shell of the head guard.

The invention has the above and other objects, all of which will be explained and more thoroughly understood when read in conjunction with the accompanying drawings which illustrate an embodiment of the invention, it being obvious that changes and modifications thereof may be made without departing from the spirit of the appended claims forming a part hereof.

In the drawings:

Figure 1 is a longitudinal central section of a head guard showing the arched auxiliary inner crown member secured in place in the outer shell of the head guard.

Figure 2 is a section on line 2-2 of Figure 1 looking toward the interior of the head guard and showing the auxiliary crown member secured in place in the outer shell, and,

Figure 3 is a plan view of the inner aux-

iliary crown member showing the looped tabs with one of the tabs extended from the main body portion of the member for better illustration.

5 The helmet or head guard within which the auxiliary inner crown member of the invention is located, is constructed with the relatively stiff leather outer main crown piece 10, which fits over the top of the head 10 of the wearer. This leather crown piece, which extends approximately to the temples of the wearer, is reinforced by a longitudinal strip 11 of relatively stiff leather, which extends from the end 12 depending from the 15 front edge of the crown piece 10, over the crown piece, and to the other end 13 depending below the rear edge of the crown piece. A transverse or cross strip 14, also of relatively stiff leather, extends from one 20 end 15 at one side of the head guard, across the crown piece beneath the reinforcing strip 11, to the other end 16 on the opposite side of the head guard, both ends of the reinforcing strip 14 depending below the 25 lower edge of the crown piece 10. The helmet or head guard is provided with additional reinforcing strips 17 and 18, which extend from the lower edge of the crown piece 10 upwardly and terminate beneath 30 the longitudinal and transverse cross strips 11 and 14. It will be obvious that as many reinforcing cross strips as may be desired may be secured to the main leather crown piece of the head guard. It will also be 35 understood that all of these reinforcing strips may be secured to the crown piece in any desired manner, preferably by stitching.

40 The head guard is provided with combined head bands, ear and temple pieces, such as are illustrated at 19. The combined head bands, ear and temple pieces are on each side of the head, and cover and protect the back of the head to the neck, the 45 ears, cheeks and temples of the player. The forehead of the player is protected by the separate frontlet protector piece 20. The forehead protector piece 20 is connected to the combined head, ear and temple pieces 50 19 through the medium of the elastics 21, 21. Because of the construction employing the elastics the frontlet piece 20 is movable relatively to the combined head, ear and temple pieces, and with them snugly fit 55 around the head of the wearer, and thus accommodate heads of various sizes. The interior of the main crown piece 10 is fitted with soft cushioning material 22, which may be of felt, sponge rubber, or the like. Likewise the combined head, ear and temple pieces, and also the frontlet protector are 60 fitted with cushioning material 23 and 24, respectively, which also may be of felt, sponge rubber, or the like. In addition to 65 the soft cushioning material 24 the forehead

protector portion is provided with an interior relatively soft leather facing 25.

The forehead protector piece 20 is suspended from the end portion 12 of the longitudinal reinforcing strip 11, and they 70 are secured to each other, preferably by means of stitching. It will thus be seen that the frontlet piece 20, suspended from the end portion 12 of the longitudinal reinforcing strip 11, is held in position by that 75 means and by the elastics 21, 21, secured in the temple portions of the combined head, ear and temple pieces 19. The frontlet piece 20 is secured to the exterior of the lower portion of the depending end 12 of the longitudinal reinforcing strip 11 so that 80 the lower edge of the crown piece 10 and the upper edge of the frontlet piece 20 are in spaced relation. This space is shown at 85 26 in Figure 1. The combined head, ear and temple protectors 19 are secured to the exterior of the depending ends 15 and 16 of the transverse crown reinforcing strip 14, and the rear depending end 13 of the longitudinal reinforcing strip 11. The combined 90 head, ear and temple pieces 19 are in spaced relation to the main crown piece 10, this space being shown at 27. The combined head, ear and temple pieces are stitched to the depending ends of the reinforcing strips 11 and 14, and are not only held thereby in suspended relation, but are further held by strips 28 and 29, stitched thereto, and to the main crown piece 10 at 95 the forward or temple portions of the pieces 10 19. These strips 28 and 29 span the space 27, and their ends are stitched to the crown piece 10 and the pieces 19.

The auxiliary inner crown member 30 is secured in the interior of the helmet or head 10 guard, and is provided with a main central portion from which looped ends extend and are adjustably secured to the main outer 11 protector shell of the head guard. It will be understood that the looped ends may be secured to the front, rear and sides of the shell, or other places in the outer portion 12 of the shell. It will also be understood that the inner crown member 30 may be a substantially straight piece of material, such as 13 rubber or elastic, extending from side to side and front to rear of the head guard, but it is preferably formed in an arch spanning the interior of the head guard, as illustrated more particularly in Figure 1 of the drawings. In the drawings the auxiliary inner crown member is shown with the loop portion 31 connected to the front of the helmet, the loop portion 32 to the rear, and the loop portions 33 and 34 to the sides of the head 14 guard. The ends of the loop portions 31, 32, 33 and 34 are provided with the loops 15 which are made from the extended tabs, which preferably have the form such as is 16 shown at 35 in Figure 3, which tabs are 17

turned upon themselves and stitched, thus forming the loops. The inner crown member will be suitably finished with hemming, or otherwise, depending upon the material which is used.

Cords or laces 36, 36 may then be drawn through the loops formed in the respective portions 31, 32, 33 and 34, and extend through the pairs of eyelet openings or apertures in the depending ends 12, 13, 15 and 16 respectively, of the reinforcing strips 11 and 14. The cord or lace in the front loop portion 31 of the inner crown member 30 extends through openings 37 and 38 in the depending end 12 of the reinforcing strip 11. The remaining cords or laces 36 secured within their respective loops in the loop portions 32, 33 and 34 are extended through the eyelet openings 39 and 40. These eyelet openings may be of any form desired but preferably do not employ metallic eyelets, since no metal is ordinarily used in the head guard. Each of the eyelet openings 39 and 40 extends through the combined head, ear and temple pieces 19, the depending ends 13, 15 and 16 respectively, of the longitudinal strip 11 and the transverse strip 14, respectively, and also through the felt or sponge rubber cushion 23 of the combined head, ear and temple protector 19. The cords or laces 36, preferably have their ends tied within the head guard, and thereby present a more finished appearance on the outside. It will also be noted from the description relative to the cords or lacing, and the eyelets, that not only is the securing of the auxiliary inner crown member inconspicuous, so far as the exterior of the head guard is concerned, but, because the cords are tied upon the inside, loose ends are not presented to an opposing player, which may be grasped by the opposing player to disconcert or harass the wearer of the head guard. It will also be noted that the eyelets 37 and 38, with the cord passing therethrough, are in the depending portion 12 of the longitudinal strip 11 coincident with the space 26, so that the frontlet piece 20 is not marred by the eyelets or the lacing, and the lacing passes over and above the soft leather cushion 25 of the frontlet piece 20. It will thus be seen that the player will not be disturbed or annoyed by a portion of the lacing being pressed against his forehead, but he will have merely the soft leather cushion against it.

It will be obvious and apparent, by reason of the employment of eyelet openings and lacing, that the inner crown member 30 is adjustable from all sides of the head guard, so that it may be raised or lowered within the interior of the head guard to fit and conform to the head of the wearer. By the employment of the inner crown member 30 a space 41 is provided between the inner

crown member 30 and the cushion member 22 of the head guard. Because of the ability to raise or lower the inner crown member 30 the space 41 may be increased or diminished according to the desire of the player. 70 In case the inner crown member 30 should become torn or soiled, the player, if he should so desire, may replace it with a new, clean inner crown member by untying the cords or lacing 36. Since the cords or lacing 36 75 have their ends within the interior of the head guard, the inner crown member may be readily removed from the ends of the cord without removing the cords from the apertures 37, 38, 39 and 40 on the front, rear and sides respectively, of the head guard. The new inner crown member may as readily be secured in place by drawing the laces through the respective loops of the new inner crown member, and tied securely in 85 place, with the air cushion and space 41 of the desired depth.

It will also be observed that when the player's head is within the helmet, with the top of the head pressed against the interior of the auxiliary crown member 30, the air space 41 lying between the auxiliary inner crown member and the main crown piece 10 forms an air cushion, which assists in protecting the player from the impacts and blows which he receives in play.

It will be understood that the head guard may be provided with ventilating apertures through the crown member 10 and the inner cushion 22 in any well known manner, and that the inner crown member 30 may also be supplied with ventilating openings of any desired number or style. Such ventilating openings have not been shown in the main crown and auxiliary inner crown member 100 and certain portions of the head protector 19, but are shown in the ear protector portion of the protector 19, at 42, in Figure 1. An aperture 43 is also shown in the ear protector portion of the protector 19 so that the 110 hearing of the player will not be interfered with.

The helmet is provided with the usual elastic chin strap 44, drawn through the openings, such as 45, in the depending ear 115 protector portion of the head protector 19.

Having thus described the invention, what I claim and desire to secure by Letters Patent is:

1. In a helmet or head guard the combination of an outer crown member, a longitudinal reinforcing strip secured to said crown member, a transverse reinforcing strip also secured to said crown member, each of said reinforcing strips having portions which depend beyond the lower edge of said crown member, and an inner crown member, said inner crown member having a plurality of loops at its perimeter, said depending ends of said reinforcing strips having apertures 120

therein, and laces secured in said loops and apertures to hold said inner crown member in adjustable and removable relation to said reinforcing strips.

- 5 2. In a helmet or head guard the combination of a main crown member of relatively stiff leather, combined head, ear and temple protectors, also of relatively stiff leather, a forehead protector, longitudinal and transverse reinforcing leather strips secured to said crown member, the ends of which are secured to said head, ear, temple and forehead protectors, apertures through the depending ends of the reinforcing strips, apertures in the head, ear and temple protectors coincident with the apertures in the depending ends of the transverse reinforcing strip and the rear depending end of the longitudinal reinforcing strip, an inner crown member in spaced relation to the inner surface of said main crown member, said inner crown member being provided with a plurality of loops and laces extending through said loops and said apertures to 10 adjustably secure said inner crown member within the interior of said head guard.
- 15 3. In a helmet or head guard the combination of a main crown member of relatively stiff leather, combined head, ear and temple protectors, also of relatively stiff leather, a forehead protector lined with relatively soft leather, longitudinal and transverse reinforcing leather strips secured to said crown member, the ends of which are secured to said head, ear, temple and forehead protectors, apertures through the depending ends of the reinforcing strips, apertures in the head, ear and temple protectors coincident with the apertures in the depending 20 ends of the transverse reinforcing strips and

the rear depending end of the longitudinal reinforcing strip, an inner crown member in spaced relation to the inner surface of said main crown member, said inner crown member being provided with a plurality of loops, and laces extending through said loops and said apertures to adjustably and removably secure said inner crown member within the interior of said head guard, the lacing in the front depending end of the longitudinal reinforcing strip passing through eyelets in said depending end between the lower edge of the main crown member and the upper edge of the forehead protector over said soft leather lining. 25

4. As a new article of manufacture an auxiliary crown member adapted to be secured in the interior of a helmet or head guard, said crown member being provided with a plurality of means whereby it may be adjustably and removably secured within said head guard, said means being in the form of loops in the outer edge of said crown member, and adapted to receive laces which may pass through apertures in said head guard. 30

5. As a new article of manufacture an arched auxiliary crown member adapted to be secured in the interior of a helmet or head guard, said arched crown member being provided with a plurality of means whereby it may be adjustably and removably secured within said head guard, said means being in the form of loops in the outer edge of said crown member, and adapted to receive laces which may pass through apertures in said head guard. 35

In witness whereof, I hereunto subscribe my name this 6th day of October A. D. 1926.

BENJAMIN E. BATES.
